UNITED STATES PATENT OFFICE.

DAVID PERLMAN, OF NEW YORK, N. Y.

CLOTH-CUTTING MACHINE.

1,168,738.

Specification of Letters Patent. Patented Jan. 18, 1916.

Application filed June 15, 1915. Serial No. 34,182.

To all whom it may concern:

Be it known that I, DAVID PERLMAN, a subject of the Czar of Russia, and resident of New York, in the county of New York 5 and State of New York, have invented certain new and useful Improvements in Cloth-Cutting Machines, of which the following is a specification.

My invention relates to certain improvements in cloth cutting machines and more particularly to that type shown in my prior Patent 1,080,518, granted December 2, 1913. In that patent I have shown a machine having a circular knife adapted to be rotated to 15 cut through a plurality of layers of cloth at the same time and I have shown certain attachments for guarding and for sharpening the knife.

One of the main objects of my present invention is to facilitate the cutting of all of the superposed layers of the material to the same distance so that the end of the cut will be straight from the top to the bottom. This is especially desirable where the design 25 includes a reentrant angle, or a corner, or a point and is also of importance in notching the edge.

Previous to my invention, this operation has been poorly performed by lifting up the 30 cloth by hand when the top layer has been cut to the desired point, in order to bring the lower uncut layer up to the normal height of the top layer. Only then will the knife cut all of the layers to the same distance. This operation is performed with 35 great difficulty and danger to the operator or cutter, as the goods must be lifted at a point very close to the sharp edge of the knife and in doing so, he is liable to bring 40 his hands in contact with the knife. It is especially dangerous when such an operation is performed some distance away from the edge of the goods which necessitates the cutter shoving his hand under the goods a considerable distance to lift it up.

In addition to being exposed to injuries in the operation of lifting the goods, the operator is liable to have his hands cut by the upper part of the knife, as the frequent 45 lifting of the goods compels the lower part of the knife guard to be in a much higher position than the actual height of the goods. This leaves an open space between the guard and the knife above the goods. In my improved construction, I keep the guard at the actual height of the cloth and provide posi-

tive and simple mechanical means for lifting the goods and automatically lifting the guard as the goods are lifted and at all times protect the operator's hand from being cut. 60

A further important object of my invention is to remove certain of the difficulties encountered in grinding the knife. In the best form of machines now in use, it is very difficult for the cutter to adjust the grinders 65 so as to make a perfectly sharp edge on the knife and furthermore, the sparks resulting from the grinding action are liable to set fire to the goods if the knife is sharpened while in the goods. It also leaves the powdered steel and stone dust on the goods which 70 damages fine white goods. I overcome all of these difficulties by my improved construction in which a person, unskilled in the adjusting of machines, can easily adjust the 75 grinders to make a perfect sharp edge. One adjustment takes care of any variation which may exist in the relative sizes of the two stones when first put in, or a variation of the rate at which they wear away, either of 80 which variations is liable to cause one stone to engage with the edge of the knife before the other. All the operator has to do is to loosen a screw and press down the grinder. The latter will automatically slide axially 85 to the proper position so as to equally engage with the opposite sides of the knife. The operator may then tighten the screw and lock the grinders in perfectly adjusted position. The other adjustment permits the 90 stones to be turned about a pivot to take up for wear when the stones have been used for some time.

A further object of my invention is to protect the goods from the sparks which are 95 caused when the knife is being sharpened and to take up the powdered steel and stone dust. For this I have provided a set of brushes which come in close contact on both sides of the knife and prevent any sparks 100 from passing through. The brush edges may be constructed of fire-proof material and the brush is so mounted that it can easily be swung out for the purpose of cleaning, but in normal operation, is automatically kept in proper position by means of the 105 spring which tends to hold both brushes always in the same position.

A further object of my invention is to lock the knife guard in position so that it 110 cannot be swung outward except by the act of bringing the grinders into position to

sharpen the knife. At all other times the guard is so locked that it cannot be pressed aside either accidentally or intentionally. Furthermore, the guard will not swing aside by the lowering of the grinders unless the cloth lifter be in lowered position.

5 My invention embodies various other important features and permits the securing of various other important objects which will 10 be pointed out more particularly herein-after.

In the accompanying drawings, I have 15 illustrated certain embodiments of my invention, but I wish it particularly understood that various other embodiments may be designed within the spirit and scope of my invention as defined in the appended 20 claims. I desire the particular forms shown in the drawings to be considered merely as 25 illustrative of the invention and not as limitations thereof.

In these drawings, to which reference is 30 to be made, and on which similar reference characters indicate corresponding parts in the several views, Figure 1 is a side elevation of a machine constructed in accordance with my invention, the base thereof being shown in section and the parts in normal operating position; Fig. 2 is a transverse 35 section taken in part on the line 2--2 of Fig. 1; Fig. 3 is a vertical section taken in part on the line 3--3 of Fig. 1; Fig. 4 is a perspective view of portions of some of the 40 separated parts embodied in the guard lifting and locking mechanism; Fig. 5 is a face view of certain of the parts shown in Fig. 4; Fig. 6 is a top plan view of the grinders and their support; Fig. 7 is a face view of the grinders, brushes and their support; Fig. 45 8 is a face view of the cloth lifting mechanism; Fig. 9 is a view similar to a portion of Fig. 3, but on a very much enlarged scale; Fig. 10 is a face view of a portion of the cam shown in Fig. 9; Fig. 11 is a perspective view of the grinders showing their relationship to the knife during the grinding operation; Fig. 12 is a view similar to Fig. 1, but showing the cloth raising mechanism in elevated position to the maximum extent 50 and showing the grinders, in dotted lines, in grinding position; Fig. 13 is a view similar to Fig. 1, but showing a modified form of guard and grinder support, and Fig. 14 is a sectional detail of a part shown in 55 Fig. 13.

I have illustrated my invention as applied to a type of cloth cutting machine in which there is a flat plate or base 20 adapted to slide on a table beneath the cloth to be cut. 60 This base carries a standard 21 also in the form of a substantially flat plate having a bracket 22 at the upper end for supporting an electric motor 23 or any other suitable driving means.

65 The standard 21 has a stub-shaft 24 car-

rying the circular cutting knife 25 and a beveled gear 26 rigid with said knife. A shaft 27 extends downwardly through the bracket 22 from the electric motor and carries at its lower end a pinion 28 meshing 70 with the gear 26 to rotate the knife in a vertical plane when the motor is running. The lower edge of the knife extends into a slot 29 in the base 20 and this base has an inclined upper surface for permitting it to 75 easily slide beneath the cloth and permit the latter to ride over the upper surface of the base and up an inclined guide member 30 to the edge of the knife.

The parts so far described in detail do not, 80 by themselves, constitute any portion of my present invention as they are shown in very similar form in my prior Patent No. 1,080,518.

It will be noted that as the knife is circular and rotates in a vertical plane, the operation of the cutting edge of the knife at the elevation of the axis is farther in advance than any other part of the cutting edge. Therefore, as the machine, as shown in Fig. 1, is pushed toward the left and as the large 85 number of superposed layers of goods ride up over the guide 30 to the cutting edge of the knife, the upper layers will be cut through to a greater distance from the edge than are the lower layers. This is of course 90 immaterial so long as the goods are continually cut along a straight or approximately straight line, but when the knife comes to the end of the line or it is desired to turn a sharp angle, or it is desired to notch the 95 goods, it is important that all of the layers be cut through to the same distance. As has been previously pointed out, this has been done by the operator who inserts his hand beneath all of the layers and raises up the 100 goods adjacent to the cutting edge of the knife so that the lower layers will come to the elevation previously occupied by the upper layer. It is not necessary to raise them to the height of the axis of the knife as the 105 goods will bend and will be presented at an acute angle to the horizontal.

In my improved construction I provide a device for mechanically lifting the goods at this point so as to avoid the necessity of the 110 operator bringing his hand adjacent to the cutting edge. This device is shown separate from the machine in Fig. 8. The lifting device in the form shown is a curved 115 plate 33 of a diameter a little larger than the diameter of the knife. The plate is set into an annular recess in the face of the standard or frame 21 so that its outer surface lies substantially flush with the outer 120 surface of said frame, and thereby permits the knife to lie closely adjacent to the frame as shown particularly in Figs. 3 and 9. To 125 retain the lifter in position, the curved recess which follows the contour of the cutting edge of the knife, is under-cut and the 130

sides of the lifter are beveled so that the lifter can be removed only by an endwise movement out of the recess or groove. The lifter has a comparatively close fit in the recess or groove, but may be moved endwise within the groove as desired. With the parts in the normal position, the operating end 34 of the lifter normally lies substantially flush with the upper surface of the guide 30 so that the cloth may readily pass over the end of the lifter. When it is desired to lift the goods, the lifter is moved endwise, that is, circumferentially of the knife, so that the lifting end raises the goods at a point closely adjacent to the cutting edge of the knife to the desired distance. In Fig. 12 I have shown the lifter in maximum raised position although it is not ordinarily essential that the lifter have as great a range of movement as is shown.

The upper end of the lifter is preferably of somewhat greater width than the lower end and includes a plate portion 35 to which is attached the base portion 36 of an operating handle 37. By moving this handle downwardly and rearwardly, for instance from the position shown in Fig. 1 to the position shown in Fig. 12, the lifter is given the desired movement. The lower rear edge 30 of the knife is normally protected by a flange 38 formed integral with the standard 21 in order to permit the operation of the lifter and to protect the upper part of the rear edge when the lifter is in normal position. I cut away the upper portion of this flange and provide the lifter 33 with a flange 39 standing out substantially at right angles to the plane of movement of the lifter and disposed closely adjacent to the periphery of the knife. This flange 39 telescopes inside of the flange 38 when the lifter is operated as shown in Fig. 12 and it in effect forms an upper extension of the flange 39 to protect the upper edge of the knife when the lifter is in normal position, as shown in Fig. 1. The upper end of the flange 38 may, if desired, constitute the stop with which the handle 37 engages, to limit the movement of the lifter in one direction, as shown in Fig. 12, while movement in the opposite direction may be limited by a stop or pin 40 on the frame, as shown in Fig. 13. Other forms of stops may be employed or they may be omitted.

It is not essential that the lifter be of the specific form shown in the drawings as it is evident that any means normally disposed beneath the cloth, closely adjacent to the cutting edge of the knife and adapted to be raised and follow, or approximately follow, the cutting edge, may be used for the purpose. For instance, the body portion of the lifter 33 might be in the form of a wire rather than the flat plate with beveled edges as shown. If the guiding groove or recess

proper retains the lifter, it might be flexible, and in fact a certain amount of flexibility is necessary in the part shown in order to insert it endwise into the groove.

For guarding the upper front portion of the cutting edge of the knife, that is, the portion which is above the cloth, I provide a guard which I automatically raise as the goods are raised. This guard may assume various different forms, two of which I have illustrated in the accompanying drawings. In the specific form shown in Figs. 1, 5 and 12, the guard is in the form of a curved plate 42 extending downwardly and forwardly along the edge of the knife from the upper side approximately to the level of the top of the goods. This plate has a flange 43 extending across the edge of the knife as shown particularly in Fig. 9. The flange may, if desired, enter a corresponding groove 44 in the outer surface of the plate portion 35 of the lifter. This is shown particularly in Figs. 8 and 9. The plate 42 is adjustable circumferentially of the knife in order to adjust it to different thicknesses of goods. The plate is preferably carried by a plate 45, the two being connected by two pins or studs 46 carried by the plate 45 and extending through a slot 47 in the plate 42. These permit the endwise movement of the plate 42 in respect to the plate 45. It is not ordinarily necessary to provide any locking means for holding the two plates in the desired adjusted position as I may employ a very thin, flat plate spring 48 connecting the inner ends of the two studs 46 and having its center portion resiliently pressing against the inner surface of the plate 42. This spring need be hardly thicker than a sheet of bristol-board and by its resiliency will frictionally hold the plates 42 and 45 in the desired adjusted position.

In order to automatically raise the guard 42 as the lifter is raised and thus prevent the guard from interfering with the free upward movement of the goods, I connect the plate 45 to the plate portion 35 of the lifter so that the guard will move circumferentially of the knife at the same time and to the same extent as does the lifter. To permit the guard to be swung laterally away from the knife and to thus permit the knife to be cleaned, adjusted, ground or removed, I pivotally connect the parts. As shown, the base portion 36 of the handle 37, which is connected to the plate 35 of the lifter by small screws, is hinged to the plate 45 of the guard. In the specific construction illustrated, these two members have pintle sleeves formed integral therewith to receive a pintle 50. A coil spring 51 encircles the pintle and normally holds the guard in position and normally resists the swinging of the guard outwardly from the position shown in

dotted lines in Fig. 9 to the position shown in solid lines.

For swinging the guard outwardly to permit the grinding of the knife, I may provide various different mechanisms. In the specific form shown, this includes a lever 54 pivotally mounted upon the side of the frame or standard opposite to the knife and adapted to be swung in a vertical plane. As shown, the frame has a rearwardly extending stud or stub shaft 55, shown particularly in Fig. 2, upon which this lever is mounted and encircling the stud is a coil spring normally holding the lever in the position indicated in Fig. 1. This lever has a portion adjacent to the main handle 56 of the machine, while the opposite extremity of the lever is designed to carry the grinders hereinafter described. Pivotally mounted upon the standard 21 and beneath the motor supporting bracket 22 is a cam lever 57, shown on a greatly enlarged scale in Figs. 9 and 10. This pivoted cam lever 57 is normally swung outwardly to the position shown in dotted lines in Fig. 9 by a small spring 58, or by any other suitable means. The outer surface of the cam lever lies in the path of movement of the lever 54 which latter may, if desired, carry an anti-friction roller 59. The lever 54 and the cam lever 57 are normally in the position shown in dotted lines in Fig. 9.

Projecting through the frame 21 of the machine is a pin 60, one end of which is adapted to engage with the pivoted guard and the other end of which is adapted to be operated by the cam 57. The point or pressing end of the pin normally lies substantially flush with the inner surface of the groove or recess in which the plate 35 travels and it may be withdrawn to this position by any suitable form of operative connections between the pin and the cam lever. Merely by way of example, I have shown the pin provided with a transversely extending head 61, slidable in a T-shaped slot 62 in the face of the cam lever 57, so that as the latter is swung to the position shown in dotted lines in Fig. 9, it will automatically withdraw the pin to inoperative position. As the lever 54 is depressed, the roller travels along the outer cam surface of the cam lever 57 and swings the latter toward and to the position shown in solid lines in Fig. 9. This forces the pin endwise to the position shown in solid lines in Fig. 9 and the engagement of the point of the pin with the guard below the pintle 50 of the latter, swings the guard out to the position shown in solid lines in Fig. 9.

The specific proportion of parts shown in Fig. 9 need not be followed as the proportions may be changed to secure greater or less relative movement of the parts. It is only essential that the swinging down-

wardly of the lever shall operate to press the pin endwise and swing the guide outwardly. In practice, it may be desired to swing the guard to a considerably further distance than is shown in Fig. 9 and this may be accomplished by mounting the pin closer to the pivotal support of the guard. To prevent the pin from being wedged beneath the guard, should the latter be pressed outwardly to more nearly a horizontal position, the pin preferably engages, not merely with the inner surface of the plate 45, but preferably engages in the angle of intersection between said plate and a lug 63 on the face of said plate. As the plate approaches a horizontal position, the pressure will be against the side of the lug instead of along the surface of the plate.

As an important feature of my invention, I provide means for normally locking the guard in operative position and automatically unlocking it as the grinders are moved toward the edge of the knife. The guard is normally held in the position shown in Fig. 1 by any suitable form or arrangement of springs 65 and when in this position, the pin 60 comes into proper position in respect to the lug 63. To reach the lug it is necessary to pass through the plate 35 of the cloth lifter and in doing so it unlocks the guard and permits it to swing about the pintle and in respect to the cloth lifter.

As shown particularly in Fig. 4, the plate 35 of the lifter has a recess 66 in one end in which is mounted a slide 67, the slide being of substantially the same thickness as the plate and held in the plane of the plate, and against all movement except an endwise movement by the beveling of the edges of the slide and recess. Of course any other means might be employed for positioning and guiding the slide. The slide is held inwardly to the limiting extent in the recess by any suitable form or arrangement of spring 68. In the form shown in the drawings, this spring is in the form of a coil mounted in a pocket in the plate and having a free end for engagement with a groove 69 in the outer end of the slide. The slide and the recess at their inner ends have opposed grooves 70 defining a small passage through the plate and of smaller diameter than the pin 60, and disposed in alignment with the pin when the cloth lifter is in lowered or normal position. The slide 67 has an under-cut lug 71 on the outer face thereof adapted to engage beneath a shoulder or flange 72 on the lug 63 so that the engagement of the lugs 71 and 63 normally prevents the outward swinging of the guard. Upon lifting the free end of the lever 54, the cam lever 57 is swung downwardly and inwardly and the point of the pin enters the grooves 70 and forces the slide outwardly against the action of the

spring 68. This disengages the lug 71 from the lug 63 and thereby unlocks the guard. A further movement of the pin 60 swings the guard upwardly as above described.

5 The lever 54 at one end carries the grinders and the swinging of this lever serves to first swing the guard away from the knife edge and to later bring the grinders to the knife edge. This timing of the operation is in part secured by the particular curvature of the outer or cam face of the lever 57. It will be noted, particularly from Fig. 9, that the lower portion of this outer face is substantially parallel to the direction of movement of the lever after the cam lever 57 has been swung to final position. In other words, during the first part of the downward movement of the lever 54, the cam lever 57 and guard swing through their maximum movement and the further downward movement of the lever 54 does not materially affect the position of the cam lever 57 or the guard.

The grinder is preferably in the form of two circular stones 73 spaced a slight distance apart to permit the entry of the knife edge therebetween. The two stones are clamped on two separate sleeves 76 which latter are free to rotate on a supporting pin 30 or shaft 77. The ends of the latter are held in the ends of the two branches of a yoke 78. As shown, the pin or shaft 77 is in the form of a bolt, one end having a slotted head and the other end being threaded to retain it in the yoke, and neither end projected out beyond the yoke to any considerable extent. Each stone has a peripheral wall and an end wall so as to leave a chamber therein. It is the end walls which are clamped on the sleeves 76. I may and preferably do provide each sleeve with a flange at its outer end for engagement with the outer surface of the end wall of the stone, and a nut threaded along the body portion 40 and engaging with the inner surface of the end wall. The two sleeves, by abutting, limit the movement of the stones toward each other.

As an important feature, I utilize the opposed faces of the two stones as the grinding surfaces rather than using the periphery of the stones. The yoke 78 is pivotally supported on a bracket 79 and the bracket and yoke are provided with extensions in one of which there is a grooved slot 80 and in the other of which there is a screw 81 so that the clamp and the stones carried thereby may be swung about the pivotal connection 82 and thus rotate in planes 83 at a slight angle to the plane of the plate. If they are rotated in the same plane, it is evident that neither stone would engage with the edge of the knife if the stones were properly spaced axially, but by spacing the

adjusting them about the pivotal support 82, the edge of one stone may be made to engage with one side of the knife at the cutting edge, and the edge of the other stone will simultaneously engage with the opposite surface of the knife at the cutting edge, but at a point spaced circumferentially along the cutting edge. Very little of this tilting adjustment is necessary when the stones are new and are spaced only a very slight distance apart, but as the surfaces of the stones wear away, the screw 81 may be loosened and the stones tilted to a greater extent so as to insure the proper engagement of the stones with opposite sides of the knife. This is the only adjustment which is ordinarily necessary during the length of the life of the stones. In originally mounting the stones, it is necessary that the space between them be properly centered in respect to the plane of rotation of the knife. To secure this, I connect the bracket 79 to the lever in such a way that the stones may be adjusted in the direction of their axis. As shown particularly in Fig. 6, the lever 54 has an end portion 83 extending substantially parallel to the axis of the knife, and the bracket 79 has a slot 84 receiving a square stud 85 and a clamping screw 86. By loosening the screw, the bracket may be adjusted lengthwise or the end portion 83 of the lever and the space between the two stones properly centered in respect to the knife.

The stones normally occupy a raised position away from the knife and above the guard as is shown in Fig. 1 although in actual practice, I prefer to vary the proportions of the parts so as to bring the stones closer to the motor support and closer to the knife. I have shown them in the proportion shown in Fig. 1 for clearness and to avoid confusion in the drawing. I have shown them more nearly in the desired position in Fig. 13 which involves a modified form of guard and guard operating means. I have also shown the grinders of a slightly larger size than it might be found desirable to employ. In order to prevent the grinders from being pressed on to the knife to such an extent that when the grinders are worn away the knife can come into contact with the axle or other supporting parts of the grinder, I may provide any suitable form of stop. This stop may, if desired, be constructed as a part of the cam lever 57 although any other construction of stop might be employed under varying conditions. The cam lever 57 is shown as having a short extension 89 against which the lever 54 may abut when at the desired lower limit of its movement.

As an important feature of my invention, I provide means for collecting the grinding stone dust and fine steel particles resulting

from the grinding operation and prevent sparks from flying on the goods in case the knife is ground while the machine is in the goods. In the specific form illustrated, 5 I pivotally connect two arms 90 to the side of the extension 83 of the grinder supporting lever and curve the end of each arm so that it substantially follows the contour of the grinders. Each of the two arms carries a 10 brush 91 and the two brushes are so disposed as to engage with opposite surfaces of the knife while the grinding operation is going on. In fact, the two brushes may directly contact and the knife may enter 15 between and spread them slightly apart. The brushes are preferably formed of material which is non-combustible and are so constructed that they are not readily cut by the knife. A preferred form is to make 20 the inner portion of each brush of asbestos fibers and make the outer layer of each brush of very fine wires. To hold the brushes in position but at the same time to permit them to be readily swung outwardly 25 as shown in dotted lines in Fig. 7, I connect each brush arm 90 to the side of the lever part 83 by a pivot pin 92 and provide angular surfaces on the brush arm for direct engagement with a spring 93. The spring, in 30 pressing against the flat end of the arm, tends to hold the arm and the brush in the position shown in Fig. 7, but the two brushes may be readily swung away from each other and against the tension of the springs and 35 may be held temporarily in such spaced relationship by the pressure of the springs on another face or angle at the end of the brush arm.

It will be noted that the brushes are connected to the lever end 83 entirely independently of the supporting or adjusting means for the grinding stones. The brushes are so set that the meeting edge of the flexible or fiber portions are in the plane of the cutting edge and as the brushes move in a plane parallel to the plane of the knife, no adjustment of the brushes is necessary. It is merely the grinders which need to be initially adjusted axially to bring the line between them into the plane of the cutting edge, and readjusted from time to time to restore this condition in case one stone wears away faster than the other. The stones are never adjusted toward or from each other but as they wear away equally, they are tilted or swung to a greater extent about the pivot 82.

In the foregoing description of the specific form illustrated in Figs. 1 to 12 inclusive, 60 I have indicated certain alternative arrangements and have emphasized the fact that other specific means might be employed for accomplishing various minor desirable results. I do not wish to be understood as in any way limiting myself except as required

by the prior art, as various other changes may be made.

In Figs. 13 and 14, I have illustrated substantially the same form of cloth lifter, grinders, or grinder support as that heretofore described, but I have illustrated a different form of guard. This guard is in the form of a channel shaped bar 95 vertically movable within a channel shaped guide 96 connected to the upper part of the machine 75 by a bracket 97. The guard is thus mounted directly on the machine instead of on the cloth lifter. For simultaneously raising the guard and the cloth lifter, I provide a lever 98 pivotally connected to a bracket 99 on the 80 frame of the machine or to any other suitable supporting part. The opposite ends of the lever are connected to the cloth lifter and to the guard. As shown, the lever has a slot 100 at one end receiving a pin 101 on the 85 cloth lifting lever 37, while the opposite end is provided with a slot 102 receiving an adjustable connecting member 103 carried by the guard 95. As shown, this connecting member 103 is in the form of a bolt with a 90 projecting head adapted to permit it to be readily turned by hand. Within the channel member 95 is a non-rotatable nut 104 adapted to engage with the inturned edges of the channel member constituting the guard 95. 95 By tightening this connecting member, the nut is forced against the flange while the end of the member abuts against the web part of the channel and the member is thus rigidly connected to the guard. At the same time, 100 it may freely slide within the guide 96. The guard is easily adjusted to different thicknesses of cloth by loosening the bolt and sliding the guard to the desired position. In 105 Fig. 13, I have shown the guard at a somewhat greater distance from the edge of the knife than would ordinarily be employed in practice. It is desirable to bring the guard as close to the knife as convenient so as to reduce the liability of the operator bringing 110 his hand accidentally into engagement with the cutting edge of the knife. The lower end of the guard may be made in any suitable manner to prevent it from catching in the cloth. As shown, it presents a curved surface constituting a shoe 105. The form of 115 this may be varied at will.

Having thus described my invention, what I claim as new and desire to secure by Letters Patent is:

1. The combination with a circular knife, of a curved cloth lifting member disposed adjacent to the periphery thereof and movable circumferentially to vary the elevation of the goods in respect to the axis of the 125 knife.

2. The combination with a circular knife and a support therefor, of a curved cloth lifting member carried by the support and movable circumferentially, the said member 130

leaving a radius of curvature slightly larger than the radius of said knife.

3. The combination with a circular knife, of a support therefor, disposed closely adjacent to one surface of the knife and having a curved recess in the face thereof toward said knife and opposite the cutting edge of the latter, and a member disposed within said recess and movable along said recess, one extremity of said member being adapted to engage with the material to be cut to vary the elevation of the latter in respect to the axis of the knife.

4. The combination with a circular knife, of a support therefor, and a curved member supported and guided by said knife support and movable along a path approximately following the cutting edge of the knife, one extremity of said member being normally disposed beneath the path of movement of the material to be cut and when operated, serving to lift the goods along the cutting edge of the knife.

5. The combination with a circular knife, of a member supported independently thereof and movable along the periphery of the knife, one portion of said member projecting out radially beyond the edge of the knife and presenting a cloth lifting surface and another portion of said member extending transversely across the cutting edge of the knife and constituting a guard for the latter.

6. The combination with a circular knife, and a support therefor, of a device secured to said support, one extremity of said device presenting a cloth lifting surface and another portion of said device constituting a guard for the exposed portion of the knife above the cloth.

7. The combination with a circular knife, and a support therefor, of a device secured to said support, one extremity of said device presenting a cloth lifting surface and another portion of said device constituting a guard for the exposed portion of the knife above the cloth, the said guard being adjustable toward and from the extremity of the cloth lifting surface.

8. The combination with a circular knife, and a support therefor, of a device secured to said support, one extremity of said device presenting a cloth lifting surface and another portion of said device constituting a guard for the exposed portion of the knife above the cloth, the said guard being adjustable toward and from the extremity of the cloth lifting surface and along the cutting edge.

9. The combination with a circular knife, of a curved cloth lifting member movable along the periphery of the knife, and a guard member secured to said cloth lifting member and adjustable circumferentially of the knife and in respect to said cloth lifting member.

10. The combination with a circular knife, of a curved cloth lifting member movable along the periphery of the knife, and a guard member pivotally secured to said cloth lifting member and adjustable circumferentially of the knife and in respect to said cloth lifting member.

11. The combination with a circular knife, of a curved cloth lifting member movable along the periphery of the knife, a guard member pivotally secured to said cloth lifting member and adjustable circumferentially of the knife and in respect to said cloth lifting member, and manually operable means for swinging said guard about the pivotal connections between the latter and said cloth lifting member.

12. The combination with a circular knife, of a guard, a support therefor mounted to move circumferentially of the knife, and frictional sliding connections between said guard and said support.

13. The combination with a circular knife, of a guard, a support therefor mounted to move circumferentially of the knife, frictional sliding connections between said guard and said support, and means for swinging said guard and support outwardly away from the knife and independent of any circumferential movement.

14. The combination with a circular knife, of a guard, a support therefor mounted to move circumferentially of the knife, sliding connections between said guard and said support, and means for swinging said guard and support outwardly away from the knife and independent of any circumferential movement.

15. The combination with a circular knife, of a member movable along a curved path approximately following the cutting edge of the knife, a plate pivotally secured to said member about an axis approximately tangential to the cutting edge, and a guard carried by said plate.

16. The combination with a circular knife, of a member movable along a curved path approximately following the cutting edge of the knife, a plate pivotally secured to said member about an axis approximately tangential to the cutting edge, and a guard carried by said plate and adjustable circumferentially of the cutting edge and in respect to said plate and said member.

17. The combination with a cloth cutting knife, of a cloth lifter normally disposed below the path of movement of the cloth, and a knife guard for the exposed edge of the knife above the cloth, said lifter, cloth and guard being movable upwardly simultaneously.

18. The combination with a cloth cutting knife, of a cloth lifter normally disposed below the path of movement of the cloth, a knife guard for the exposed edge of the cloth.

- knife above the cloth, and means for simultaneously raising said lifter and said guard to approximately the same extent.
19. The combination with a circular cloth cutting knife, of a cloth lifter normally disposed below the path of movement of the cloth, a knife guard for the exposed edge of the knife above the cloth, and means for simultaneously raising said lifter and said guard to approximately the same extent.
20. The combination with a circular cloth cutting knife, of a cloth lifter normally disposed below the path of movement of the cloth, a knife guard for the exposed edge of the knife above the cloth, and means for simultaneously raising said lifter and said guard.
21. The combination with a circular knife, of a guard for a portion of the edge of the knife, and a curved member movable along a curved path approximately following the cutting edge of the knife, one end of said member presenting a cloth lifting surface, and the opposite end of said member constituting a support for said guard.
22. The combination with a circular knife, of a cloth lifting member movable upwardly along the cutting edge of said knife, a guard disposed above and spaced from said lifting member and also movable upwardly simultaneously with said cloth lifting member, and means for guiding said guard and preventing movement thereof toward and from the knife.
23. The combination with a circular knife, of a cloth lifting member movable upwardly along the cutting edge of said knife, a guard disposed above and spaced from said lifting member and also movable upwardly, and operative connections for moving said member and said guard simultaneously.
24. The combination with a circular knife, of a support therefor, a guard carried by said support, and means for moving said guard along a curved path approximately following the cutting edge of the knife and independent means for swinging said guard away from said cutting edge.
25. The combination with a circular knife, of a support therefor, a guard carried by said support, means for moving said guard along a curved path approximately following the cutting edge of the knife and independent means for swinging said guard away from said cutting edge, and locking means normally preventing said swinging movement.
26. The combination with a cloth cutting knife, of a guard pivotally mounted to swing upwardly and from the cutting edge, locking means for normally preventing said swinging movement, and means for simultaneously unlocking said guard and swinging it.
27. The combination with a cloth cutting knife, of a guard normally disposed adjacent the cutting edge and adjustable along said edge, a pivotal support for said guard permitting the latter to be swung toward and from said cutting edge, means for normally locking said guard against swinging movement, and means for swinging said guard.
28. The combination with a cloth cutting knife, of a guard normally disposed adjacent the cutting edge and adjustable along said edge, a pivotal support for said guard permitting the latter to be swung toward and from said cutting edge, means for normally locking said guard against swinging movement, and means operable only when said guard is in a predetermined, circumferentially adjusted position for swinging said guard.
29. The combination with a circular knife, of a guard for the cutting edge, a support for said guard and movable along the cutting edge, pivotal connections between said guard and said support, locking connections between said guard and said support and normally preventing movement about the pivotal connections, and means operating to unlock the guard and swing the same upwardly when the guard support is in a predetermined position circumferentially of the knife.
30. The combination with a circular knife, of a guard, a support movable along the cutting edge, pivotal connections between the guard and the support, a slide carried by said support and having locking engagement with said guard, and a member movable to first move the slide to inoperative position and then swing the guard in respect to the support.
31. The combination with a circular knife, of a guard, a support movable along the cutting edge, pivotal connections between the guard and the support, a slide carried by said support and having locking engagement with said guard, and a pin movable endwise to first move the slide to inoperative position and then swing the guard in respect to the support.
32. The combination with a circular knife, of a cloth lifting member, a guard for the knife edge, a pivotal support for said guard, and means for swinging said guard about its pivotal support, said means being inoperative save when said cloth lifting member is in a predetermined position.
33. The combination with a cloth cutting knife, of a cloth lifter, a knife guard movable toward and from the cutting edge, and means for moving it away from the cutting edge, said means being inoperative save when the lifter is in a predetermined position.
34. The combination with a cloth cutting knife, of a guard, a support therefor, pivotal

connections between said guard and said support, means for moving said support in respect to said knife, a pin movable endwise into engagement with said guard to swing it about its pivotal connections with its support, the movement of the support from a predetermined position in respect to the knife serving to render said pin inoperative.

35. The combination with a circular knife, of a pivotally supported guard, a pin movable endwise for swinging said guard about its pivotal support and away from said knife, a cam lever engaging with said pin, and a grinder operating lever movable along one side of said cam lever to swing the latter.

36. The combination with a circular knife, of a support therefor, a pin movable back and forth through said support, a guard for the cutting edge of the knife and movable to inoperative position upon the endwise movement of the pin in one direction, a cam lever pivoted to said support and engaging with one end of said pin, a second lever pivoted to said support and having engagement with said cam lever, and grinders carried by said second mentioned lever whereby the movement of said second mentioned lever in one direction moves said cam lever and pin to move the guard to inoperative position and simultaneously brings the grinders into engagement with the knife.

37. The combination with a circular knife and a support therefor, of a lever pivoted to said support and having a terminal portion substantially parallel to the axis of the knife, a pair of circular grinders spaced a slight distance apart and between which the edge of said knife may enter, and means for simultaneously adjusting the two grinders along the terminal portions of said lever to bring the space between the grinders into the plane of the cutting edge.

38. The combination with a circular knife and a support therefor, of a lever pivoted to said support and having a terminal portion substantially parallel to the axis of the knife, a pair of circular grinders spaced a slight distance apart and between which the edge of said knife may enter, means for simultaneously adjusting the two grinders along the terminal portion of said lever to bring the space between the grinders into the plane of the cutting edge, and means for pivotally adjusting said grinders simultaneously about an axis at right angles to their axis of rotation.

39. The combination with a knife, of a substantially U-shaped holder, two members rotatably supported therein and held against relative axial adjustment, two grinder stones carried by said members and spaced a short distance apart to permit the entry of the knife edge therebetween, and means for adjusting said holder and

stones about an axis substantially at right angles to the rod, said axis lying in the plane of the knife.

40. The combination with a circular knife, of a substantially U-shaped holder, a rod connecting the extremities of said holder, two sleeves mounted on said rod and having their ends abutting, two grinder stones carried by said sleeves and spaced a short distance apart to permit the entry of the knife edge therebetween, means for adjusting said holder and stones about an axis substantially at right angles to the rod, said axis lying in the plane of the knife, and means for adjusting said holder in a direction parallel to the axis of the knife.

41. The combination with a knife, of a pair of circular grinding stones spaced apart to receive the edge of the knife therebetween, and a pair of brushes disposed adjacent the opposite sides of said knife below the points of engagement with said stones.

42. The combination with a knife, of a pair of circular grinding stones spaced apart to receive the edge of the knife therebetween, and a pair of dust-collecting brushes adjacent the opposite sides of said knife below the points of engagement with said stones.

43. The combination with a knife, of a pair of circular grinding stones spaced apart to receive the edge of the knife therebetween, a pair of brushes disposed adjacent the opposite sides of said knife below the points of engagement with said stones, and means for adjusting the position of the stones in respect to the knife and independently of the support for the brushes.

44. The combination with a circular knife, of a pivoted lever, a pair of brushes carried by said lever and adapted to engage with opposite sides of the knife, and a pair of grinders independently carried by said lever and adapted to engage with opposite sides of the knife.

45. The combination with a circular knife, of a pivoted lever, a pair of brushes carried by said lever and adapted to engage with opposite sides of the knife, a pair of grinders independently carried by said lever and adapted to engage with opposite sides of the knife, and means for adjusting said grinders in respect to said lever.

46. The combination with a circular knife, of a pair of brushes, a pair of grinding stones, a movable supporting member carrying said brushes and stones for bringing them into operative position in respect to the knife, a clamping device for holding said stones in predetermined adjustment in respect to said member, and resilient means for retaining said brushes in predetermined relationship in respect to said member.

47. The combination with a circular knife, of a grinder for sharpening the knife and a

brush for collecting particles resulting from the grinding action, said brush including asbestos fibers.

48. The combination with a circular knife, of a grinder for sharpening the knife, and a brush for collecting particles resulting from the grinding action, said brush including asbestos fibers and fine protecting and supporting wires.

49. A cloth cutting machine having a circular knife rotatable about a horizontal axis, grinders movable into or out of engagement with the knife and spark arresting means operatively disposed adjacent to said grinders.

50. A cloth cutting machine having a circular knife rotatable about a horizontal axis, grinders movable into or out of engagement with the knife and spark arresting means operatively disposed below said grinders.

51. A cloth cutting machine having a circular knife rotatable about a horizontal axis, grinders movable into or out of engagement with the knife; and spark arresting means operatively disposed below said grinders and upon opposite sides of said knife.

52. A cloth cutting machine having a supporting plate adapted to move beneath the goods to be cut, a standard carried thereby, a circular knife carried by said standard and having its lower edge projecting into said supporting plate, a grinder normally disposed above said knife and movable downwardly into engagement with the upper portion of the cutting edge above the goods, and means disposed between the goods and said grinder for preventing the passage of dust particles or sparks from the grinder to the goods.

53. A cloth cutting machine including a supporting plate, a standard carried thereby, a circular knife mounted on said standard and having the lower edge projecting into said supporting plate, a lever pivoted to said standard, a grinder carried by one end of said lever and movable into engagement with the knife upon the swinging of the lever and spark arresting means disposed between said grinder and goods disposed upon said supporting plate and adjacent to the cutting edge.

54. A cloth cutting machine having a circular knife, means for raising the cloth at a point adjacent to the cutting edge of the knife, means for sharpening the knife at a point directly above said cloth raising means, and means for preventing the operation of said sharpening means when said cloth raising means is in raised position.

55. A cloth cutting machine including a circular knife, a handle for advancing the knife, means for varying the elevation of the cloth in respect to the axis of the knife, said means having a manually operable portion adjacent to said handle, a knife sharp-

ener, a lever pivoted intermediate of its ends and having said knife sharpener supported at one end and having the opposite end disposed adjacent to the said handle, and means for preventing the movement of said knife sharpener into engagement with the knife except when said cloth lifter is in a predetermined position.

56. A cloth cutting machine including a support, a circular knife carried thereby, a handle for advancing said support and knife and a lever pivoted to said support and knife and having one end disposed adjacent to but below said handle, and having a knife sharpening device movable into engagement with said knife upon the movement of said first mentioned lever end upwardly toward said handle.

57. A cloth cutting machine including a support, a knife carried thereby, a handle for advancing said knife and support, a lever pivoted to said support and movable in a vertical plane, one end of said lever being disposed adjacent to said handle and the opposite end having a knife sharpening device carried thereby.

58. A cloth cutting machine having a knife, a lever pivoted to swing in a plane parallel to the plane of the knife, a grinder holder secured thereto and adjustable about an axis lying in the plane of the knife, a pair of spaced grinders carried by said holder and movable into engagement with opposite surfaces of the knife upon the swinging of said lever and a pair of dust and spark collectors carried by said lever and movable into positions upon opposite sides of the knife and below said grinders upon the swinging of said lever.

59. A cloth cutting machine having a knife, a standard for supporting the same, a movable member secured to said standard, a grinder holder carried by said member, a pair of grinders carried by said holder adapted to occupy positions upon opposite sides of said knife upon the movement of said member in one direction and a pair of dust and spark collectors secured to said member independently of said grinder holder and adapted to occupy positions upon opposite sides of said knife and below said grinders upon the movement of said member to bring said grinders into operative position.

60. A cloth cutting machine including a knife, a standard carrying said knife, a member mounted on said standard and having a portion movable toward and from said knife, a pair of grinders and a pair of brushes independently carried by said member, one brush and one grinder adapted to lie at each side of said knife upon the movement of said member to operative position.

61. A cloth cutting machine including a knife, a standard carrying said knife, a

member mounted on said standard and having a portion movable toward and from said knife and a pair of brushes independently carried by said member, one brush and one grinder adapted to lie at each side of said knife upon the movement of said member to operative position, said grinders being adjustable about a pivot in the plane of the knife and said brushes be-

ing adjustable toward and from the plane 10 of the knife.

Signed at New York city, in the county of New York, and State of New York this 14th day of June, A. D. 1915.

DAVID PERLMAN.
